(57) **CLAIM**

We claim the ornamental design for a fitness monitoring capsule for a wristband, as shown and described.

DESCRIPTION

FIG. 1 is top view of a fitness monitoring capsule that is removable from a wristband; section planes are indicated for FIGS. 9 and 10.

FIG. 2 is a bottom view of the fitness monitoring capsule of FIG. 1.

FIG. 3 is a left side view of the fitness monitoring capsule of FIG. 1.

FIG. 4 is a right side view of the fitness monitoring capsule of FIG. 1.

FIG. 5 is a rear view of the fitness monitoring capsule of FIG. 1.

FIG. 6 is a front view of the fitness monitoring capsule of FIG. 1; a section plane is indicated for FIG. 11.

FIG. 7 is an isometric view of the fitness monitoring capsule of FIG. 1.

FIG. 8 is an isometric bottom view of the fitness monitoring capsule of FIG. 1.

FIG. 9 is a section view of the fitness monitoring capsule of FIG. 1 taken through the horizontal section plane shown in FIG. 1.

FIG. 10 is a section view of the fitness monitoring capsule of FIG. 1 taken through the vertical section plane shown in FIG. 1; and,

FIG. 11 is a section view of the fitness monitoring capsule of FIG. 1 taken through the section plane shown in FIG. 6.

FIGS. 1 through 11 are drawn to-scale within each Figure, although the scale from Figure to Figure may vary. In particular, the section views shown herein are drawn to a larger scale than the Figures from which they are derived.

Stipple shading is used in the accompanying Figures to convey surface contouring, not texture. The fitness monitoring capsule may additionally have a transparent or translucent (although perhaps smoked or tinted) window that allows a display within the fitness monitoring capsule to be seen by the wearer. This window is not stipple shaded in the accompanying Figures, but is rendered with diagonal line hatching.

Dash-dot-dash lines are used to indicate section planes in FIGS. 1 and 6.
